UNITED STATES PATENT OFFICE.

JOSEPH A. WOLF, OF BOULDER, COLORADO.

AIR MOISTENER.

Application filed November 3, 1920. Serial No. 421,521.

To all whom it may concern:

Be it known that I, JOSEPH A. WOLF, a citizen of the United States, residing at Boulder, in the county of Boulder and State 5 of Colorado, have invented a new and useful Air Moistener, of which the following is a specification.

This invention relates to attachments for internal combustion engines, and more particularly to an attachment designed for use in connection with the carburetor for moistening the charge entering the intake manifold of the engine.

An object of the invention is to provide a device of this character which will automatically regulate the amount of moisture entering the intake manifold, according to the speed of the motor.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a side elevational view of a portion of an internal combustion engine, showing the device as applied.

Figure 2 illustrates a longitudinal vertical sectional view through the attachment,

Figure 3 illustrates a sectional view taken on line 3—3 of Figure 2.

Referring to the drawing in detail, the reference character 5 designates the outer or main receptacle of the attachment which has an offset portion 6 constituting an overflow device communicating with the main receptacle or casing through the opening 7 so that the water level within the main receptacle may be maintained in spaced relation with the bottom wall of the inner receptacle 8.

This inner receptacle is preferably circular in cross section to conform to the shape of the main receptacle 5, the walls of the inner receptacle being disposed in spaced relation with the walls of the main receptacle to provide passageways to permit air to pass downwardly through the main receptacle to contact with the water therein.

A pipe 9 has communication with the in-

terior of the main receptacle 5, and has one extremity thereof disposed within the heating chamber 10, which is in the form of a relatively long box-like member secured to the exhaust manifold 11 of the motor, so that air passing through the heating chamber 10 will be heated by contact with the manifold and pass into the main receptacle 5 in a heated condition.

Operating within the inner receptacle 8 is a reciprocating valve member 12 adapted to control the supply of air through the opening 13 formed at the base of the valve cage 8, there being provided a rod 14, of a length equal to the length of the inner receptacle 8, on which the valve 12 operates, the rod 14 being however secured within the inner chamber 8, as by means of the cross bars 15 and 16 which are secured to the valve cage 8 and disposed at opposite ends thereof. These bars 15 and 16 may be secured in position as by welding.

From the foregoing it is obvious that as the pistons move within their cylinders, the valve member 12 is moved to open the passageway between the main receptacle and valve cage 8, the valve of course opening a greater distance, owing to the increased suction caused by the speeding up of the motor, to the end that a greater quantity of moisture is fed to the carburetor, to meet the increased demand.

The valve cage 8 is shown as in communication with the carburetor 17 of an internal combustion engine, as by means of the feed pipe 18 which has one extremity secured in any suitable manner, to the air intake opening of the carburetor so that air entering the carburetor must pass through the attachment where the same picks up the moisture as before described.

In order that the fluid within the main receptacle 5, may be replenished, a filling opening 19 is provided at the upper extremity of the main receptacle 5.

It is believed that in view of the foregoing description, a further detailed description of the operation of the device is unnecessary.

Having thus described the invention, what is claimed as new is:—

In an air moistening device, a main water containing casing provided with an overflow device, a pipe extending through the top of said main casing, an inner casing supported by the pipe and held in spaced rela-

tion within the main casing, a suction controlled valve operating within the inner casing, said main casing having an air inlet opening and an outlet for moistened air, and
5 said overflow device acting to maintain the water level in the main casing always below the inner casing.

In testimony that I claim the foregoing as my own, I have hereto affixed my signature in the presence of two witnesses.

JOSEPH A. WOLF.
